UNITED STATES PATENT OFFICE.

GEORGE HILLARD BENJAMIN, OF NEW YORK, N. Y.

ART OF MANUFACTURING STEEL.

1,314,384.

Specification of Letters Patent. Patented Aug. 26, 1919.

Application filed December 5, 1914. Serial No. 875,711.

To all whom it may concern:

Be it known that I, GEORGE HILLARD BENJAMIN, a citizen of the United States, residing at New York city, in the county 5 and State of New York, have invented certain new and useful Improvements in the Art of Manufacturing Steel, of which the following is a specification.

My invention consists in certain new and 10 useful improvements in electric melting furnaces, and the method employed for operating such furnaces.

The object of my invention is the construction of a furnace wherein the E. M. F. 15 of the current used to operate the arcs is maintained constant and the temperature effects of the arc varied, as required in the metallurgical operations taking place within the furnace.

20 The temperature of an electric arc is known to be independent of its thickness or of the current passing; the temperature can be reduced by lowering the E. M. F. of the current and changing the length of the 25 arc. For economical reasons it is best to maintain a given E. M. F. and temperature. The practical utilizable temperature of an electric arc is variously stated to be between 3500° and 4000° centigrade. My invention contemplates maintaining an arc of 30 fixed temperature, and in varying the distance between the arc and the material under treatment, in accordance with the temperature which it is desired to exhibit.

35 Thus, given an arc of fixed temperature, I may, as desired, vary the distance between the arc and the material under treatment.

The accompanying drawings, which are 40 largely diagrammatic, will serve to illustrate such a construction of furnace as may be used, as well as the method of operating the furnace.

Figure 1 is a vertical section and partial elevation showing the various parts of the 45 furnace and its operating mechanism in the position the parts will occupy when the arc and the material under treatment are nearest together. Fig. 2 is a horizontal section, taken on the line II—II of Fig. 1. Fig. 3 is a 50 horizontal section and partial plan, taken on the line III—III of Fig. 4. Fig. 4 is a vertical section and partial elevation, corresponding to Fig. 1, and showing the arc and material under treatment in the posi-

tion which they will occupy when they are 55 farthest apart. Fig. 5 is a vertical section through the hearth and operating mechanism, taken on the line V—V of Fig. 4. Fig. 6 is a vertical section and partial elevation showing modifications of the arrangement shown in Fig. 1, for varying the position between the arcs and the material under treatment.

In the drawings, 10 indicates the body of the furnace. Arranged within the body of 65 the furnace are carbon electrodes 11, connected to a source of electric energy 12. 13 indicates mechanism for operating the carbons, whereby an arc 14 will be formed between their contiguous ends. 15 indicates a 70 door in the body of the furnace provided with suitable closures 16—17. 18 is a pipe in the top of the furnace; 19 indicates the hearth of the furnace. The hearth has formed in it a pouring door 20. The hearth 19 is 75 adapted to be rotated and tilted, by substantially the same means as described in my prior Patent No. 1,106,486 dated Aug. 11, 1914, to which reference is made for a further description. The hearth, with its rotating and tilting mechanism, is mounted 80 as a whole upon a plate-like casting 21, supported on the top of a piston 22 mounted in a hydraulic cylinder 23. By reason of the cylinder 23 and piston 22, the hearth and its 85 operating mechanism may be elevated and lowered, as desired. In Fig. 6 the hearth 19 and its coöperating mechanism is mounted upon the ground, indicated at 24, and the body of the furnace is connected to the 90 lower end of the piston 22 located in the cylinder 23. In the modified construction, the body of the furnace is moved relative to the hearth. This modified construction is illustrated in my prior Patent No. 95 1,080,807 dated Dec. 9, 1913, to which reference is made for further description. 25 indicates material on the hearth, to be treated. The body of the hearth 10, in both 100 constructions shown, consists of a dome roof 26 and depending side walls 27, and the hearth of a horizontal base or floor 28, and upwardly projecting side walls 29. The side walls 29 of the hearth are situated within the side walls 27 of the body, and the 105 downwardly extending length of the side walls 27 of the body and upwardly extending length of the side walls 29 of the hearth,

is such, that either the body or the hearth may be given a considerable vertical movement without exposing any metallic portion of the body to the destructive action of the heat 5 within the furnace, or permit access of external air to the interior of the furnace. In practice I find that considerable variation in temperature effects may be obtained by a small vertical movement of the body and 10 hearth relative to each other.

The operation of my improved furnace will be readily understood. The arc is established and maintained by causing the flow of a current of definite potential and value 15 between the electrodes which are kept at practically the same distance apart. Assuming that it is desired to subject the material to be treated to the maximum temperature, the hearth is moved into the position 20 shown in Fig. 1. As the treatment progresses, and assuming that it is desired the material should be subjected to a decreasing temperature, the hearth is moved progressively from the position shown in Fig. 1 to 25 the position shown in Fig. 4, *i. e.*, which represents the final or pouring position.

During the time the material is under treatment, the hearth may be rotated through the influence of the rotating mechanism 30 shown (as described in my prior Patent No. 1,106,486) and when in the final position may be emptied by employing the mechanism shown (as described in my prior Patent No. 1,080,807). During the time the material 35 is under treatment, gases or other bodies may be introduced through the pipe 18 (as is described in my prior Patent No. 1,106,486). It will be understood that it is immaterial whether the hearth is moved to 40 ward the body of the furnace or the contrary, provided the relative temperature may be varied by such movement. In carrying certain metallurgical operations into effect, it is beneficial to rotate the hearth when the 45 material on the hearth is subjected to the highest temperature, and to decrease the rotation of the hearth or to stop it entirely as the hearth is moved into zones of lower temperature, and conversely.

50 I wish it understood that I do not limit myself in any wise to a construction in which the rotation of the hearth is effected, or to the system of application of the different temperatures. In the treatment of iron for 55 the production of steel, I prefer to subject the metal and its accompanying slags and fluxes to the highest temperature at the start, and then gradually move the material out of the zone of highest temperature to zones 60 of lower temperature, thus giving the material time, to permit the evolution of the contained gases, or combination with introduced slags and fluxes, it being well understood that combinations are best effected at 65 different defined temperatures.

Having thus described my invention, I claim:

1. In an electric furnace, the combination of a body portion, means for generating electric heat of constant thermic value, a 70 hearth portion, means for rotating the hearth portion, means for producing relative movement between the means for producing electric heat and the hearth portion and for holding said specified parts in certain defined relations at different intervals during the operation of the furnace, and without exposing any portion of the furnace, except the lining, to the temperature effects of the electric heat. 75

2. In an electric furnace, the combination of a body portion, electrodes in said body portion, a rotatable and tiltable hearth portion, means for varying the distance between the material under treatment on the 85 hearth portion and the electric arc, during the operation of the furnace, and without exposing any part of the interior of the furnace, excepting the lining, to the action of the electric arc. 90

3. In an electric furnace, the combination of a fixed body portion, a vertically movable hearth portion, means for producing rotary movement of the hearth portion, a series of electrodes located in the body portion and 95 adapted, when fed with an electric current, to produce an arc of definite thermic value at a definite horizontal level in said body portion. 90

4. In an electric furnace, the combination of a fixed body portion, a vertically movable hearth portion, means for moving the hearth portion to and from the body portion, means for moving the hearth portion in a circular direction along a horizontal plane 10 relative to the body portion, a series of electrodes in the body portion, said electrodes located and adapted, when fed with an electric current, to produce an arc of definite thermic value at a definite location in said 1 body portion, together with means for advancing the electrodes to maintain the arc constant. 1

5. In an electric furnace, the combination of a body portion, a hearth portion, both of 1 said portions formed of heat resisting material, electrodes in the body portion adapted to create an arc of constant thermic value at a defined level, means for moving the hearth portion in a vertical direction in the body 1 portion and out of the body portion, and means for rotating the hearth. 1

6. An electric furnace comprising in its construction a body portion, a hearth portion, means for producing relative motion of such parts without permitting the access of atmospheric air to the interior of the furnace, electrodes having a defined horizontal position in the body portion, means for supplying the electrodes with current to

produce an arc of definite thermic value, and means for tilting the hearth, when removed from the furnace structure after the metallurgical operations are completed, to discharge the contents of the hearth.

7. An electric furnace comprising in its construction a body portion, a hearth portion, means for moving the hearth portion in the body portion in a vertical direction
- 10 relative to the body portion, means for moving the hearth portion in a circular direction relative to the body portion, both motions being effected without permitting the access of atmospheric air to the body of the furnace, and means for tilting the hearth to discharge its contents when the hearth portion is separated from the body portion.
- 15 8. An electric furnace, comprising in its construction a body portion, a hearth por-

tion, means for producing relative motion 20 between said body portion and hearth portion in a vertical and rotary horizontal direction without permitting the access of air to the body of the furnace, a series of electrodes arranged so that the arc formed between them will occupy a fixed horizontal level, a three phase generator adapted to deliver current to said arc and to establish an arc of constant thermic value, and means for discharging the hearth when the body portion and hearth are separated.

In testimony whereof I affix my signature, in the presence of two witnesses.

GEORGE HILLARD BENJAMIN.
